UNITED STATES PATENT OFFICE.

ALPHONSO S. CAMPBELL, OF WEST MEDFORD, MASSACHUSETTS, ASSIGNOR TO A. S. CAMPBELL COMPANY, OF BOSTON, MASSACHUSETTS, A CORPORATION OF MASSACHUSETTS.

CURTAIN WINDOW.

Application filed April 6, 1921. Serial No. 459,117.

To all whom it may concern:

Be it known that I, ALPHONSO S. CAMPBELL, a citizen of the United States, and resident of West Medford, in the county of Middlesex, State of Massachusetts, have invented an Improvement in Curtain Windows, of which the following description, in connection with the accompanying drawings, is a specification, like characters on the drawings representing like parts.

This invention pertains to improvements in curtain windows and this application is a continuation in part of my copending application Serial No. 304,195, filed June 14, 1919, 15 entitled "Windows for vehicles". It is among the objects of the invention to provide a curtain window of superior construction and of relatively low cost.

In the drawings, which show a preferred 20 form of one embodiment of my invention:—

Figure 1 is an elevation of a curtain window attached to its carrying fabric, a portion of the frame of the window being broken away;

Fig. 2 is a section, partly in elevation, of one of the frame elements, all other parts of the installation being omitted;

Fig. 3 is a section similar to Fig. 2, but shows the addition of a preferred form of 30 filter strip cemented to the frame element illustrated in Fig. 2;

Fig. 4 is a section similar to Figs. 2 and 3, but shows a glass cemented to the filter strip illustrated in Fig. 3;

Fig. 5 is a section through the complete 35 installation on the line 5—5 of Fig. 1, being partly in elevation; and

Fig. 6 is a section on the line 6—6 of Fig. 1, being partly in elevation.

Referring to the drawings and to the preferred form of my invention selected for 40 illustrative purposes, I preferably provide a glass-carrying frame element illustrated sectionally in Figures 2, 3 and 4 of the drawings. This frame element is preferably formed of sheet metal and, as illustrated, may comprise two stamped portions, the outer or cover portion 7 and an inner or reinforcing portion 8 which may be secured in 45 the outer portion by flanging-over the edge of the latter at 9. The inner portion 8 preferably provides a reinforcing web 10, which is preferably turned back on itself at 11, to 50 stiffen the frame element, especially against

lateral distortion or bending. The inner 55 marginal portion of the part 7 may be flanged laterally at 12 to increase the bearing surface thereof on the glass 13 and further to stiffen the frame against lateral distortion. In the pocket between the web 10 and 60 the inner edge of the outer frame portion 7, I preferably provide filler means 14 which may be a strip of uncured or partially cured rubber. The filler means 14 is preferably cemented in the groove provided between the 65 web 10 and the inner portion of the outer frame member 7, the return flange 11 of the web 10 preferably providing a seat for the filler and allowing a recess 15 into which the rubber may be pressed. 70

The glass 13 overlies and is cemented to the filler 14, the flanged edge 12 of the outer frame portion preferably lying either directly in contact with the glass or closely adjacent thereto with a very thin film of the 75 filler 14 interposed therebetween.

The glass-carrying frame element and the glass are, in effect, cemented together, so that lateral distortion of the frame element which might perhaps otherwise occur is prevented by the glass, which is very strong either in tension or under direct compressive strains. 80

The filler 14 not only waterproofs the connection between the glass and the frame, 85 but provides an extended surface adapted to conform to the glass, which may vary somewhat, and is readily cementable to the glass, forming a much stronger union than where the glass is cemented directly to the 90 metal of the frame.

The inner portion 8 of the frame member, hereinbefore described, may have holes 20 punched therethrough and, after the glass is cemented to the frame elements hereinbefore described, the apertured curtain fabric 21 may be laid over the frame elements carrying the glass and secured thereto preferably by self-tapping screws 22 passing through a frame-securing part 23 having a 95 beaded outer edge 24 and a more or less flexible inner marginal portion 25. The self-tapping screws 22 preferably pass through apertures in the securing element 23 of sufficient diameter to avoid the cutting of thread 100 therein by the self-tapping screws, while the apertures in the inner frame element 8 into which the self-tapping screws pass are 105

preferably of a diameter such that the self-tapping screws will cut threads therein. If the apertures in the inner frame element 8 are broken through rather than punched 5 through, a certain amount of the metal will be projected inwardly to provide a longer surface in which threads may be cut by the self-tapping screws, all as is best illustrated in Fig. 5 of the drawings. The curtain fabric need not be perforated for passage 10 through of the self-tapping screws, which are ordinarily, as illustrated, pointed on their ends and which separate without substantial cutting the threads of the curtain 15 fabric.

The securing element 23 and the self-tapping screws are concealed by a cover 30 which is adapted to spring over the bead 24 so that the underlying lip 31 may securely hold the cover element 30 in place 20 with its inner edge 32 which is, as illustrated, preferably flanged to provide an extended lip bearing against the glass 13. As the self-tapping screws are drawn up, the filler strip 25 14 will be pressed into its recess and the glass will be strongly pressed against the outer face of the filler strip so that, when the cement connecting these parts together dries, great strength will be imparted to the 30 frame as a whole, not only the frame element carrying the glass being reinforced by the glass itself, but the frame elements lying on the opposite side of the glass being preferably, as illustrated, similarly reinforced by reason of their being secured to the glass-carrying frame element.

A construction along the lines illustrated and described is of great advantage in connection with the manufacture of curtain 40 windows of any size and shape, but is particularly advantageous in connection with relatively large curtain windows in which the problem of stiffening the frames to prevent lateral flexing thereof away from the 45 glass is one which does not have to be overcome to any great extent in connection with relatively small curtain windows, and especially in connection with relatively small curtain windows in which the frames are 50 round or oval so that the strength of the material is enhanced by reason of its arched shape.

While I have shown and described a preferred form of one embodiment of my invention, it will be understood that changes 55 involving omission, substitution, alteration and reversal of parts, and even changes in the mode of operation, may be made without departing from the scope of my invention, which is best defined in the following 60 claims.

Claims:

1. A curtain window installation comprising, in combination, a flexible frame secured to the curtain and normally subjected 65

to distorting stresses tending to separate the upper and lower portions thereof, said frame having a glass receiving portion, a glass in said glass receiving portion, and distortion resisting filler means interposed 70 between a portion of said frame and glass to insure a more perfect bond, said glass being securely cemented to said filler means and constituting a reinforcing element whereby to prevent distortions of the frame in the 75 plane of the glass.

2. A curtain window installation comprising, in combination, a flexible frame secured to the curtain and normally subjected to distorting stresses tending to separate 80 the upper and lower portions thereof, said frame having a glass receiving portion, a glass in said glass receiving portion, and distortion resisting filler means interposed 85 between a portion of said frame and glass to insure a more perfect bond, said glass being securely cemented to said filler means and constituting a reinforcing element whereby to prevent distortions of the frame in the plane of the glass, said frame presenting 90 a relatively narrow edge adjacent one face of the glass and a recess behind said edge into which said filler means extends to strengthen the bond between said filler means and said frame under the strain of 95 said distorting stresses.

3. A curtain window installation comprising, in combination, a glass-carrying frame element for application to one side of the curtain, said frame element having a 100 body portion formed of sheet metal and providing a recess, a filler strip cemented in said recess, a glass cemented to said filler strip, and a second frame element for application to the opposite side of the curtain 105 and means for pressing the curtain material between the frame elements on opposite sides of the curtain and for pressing the glass against the filler strip, whereby when the cement is hardened the curtain window 110 frame as a whole is stiffened by said glass against distortion.

4. A frame element for curtain windows comprising, in combination, an arched sheet metal outer portion and an inner sheet metal portion within said outer portion and providing webs extending substantially at right angles to each other, one of said webs apertured for the reception of frame-securing means and the other of said webs reversely 115 bent adjacent said outer portion and presenting a seat, a filler strip pressed against said seat and cemented to said outer portion and the second of said webs, and a glass cemented to the exposed face of said filler 120 strip.

5. A curtain window installation comprising, in combination, a glass-carrying frame element for application to one side of the curtain, said frame element having 125 130

a body portion formed of sheet metal and providing a recess, filler means cemented in said recess, a glass cemented to said filler means, and the inner edge of said body portion providing a lip extending generally in a direction parallel to the adjacent surface of the glass and permitting extrusion of the filler means between said lip and the glass, whereby, when the cement is hardened, the curtain window frame as a whole is stiffened by said glass against distortion.

5 6. A curtain window installation comprising, in combination, a glass carrying frame adapted to be secured to one side of the curtain adjacent the window opening, said frame comprising an angled portion presenting a flange at an angle to the plane of the curtain and a cover frame for said angled portion shaped to provide a filler 10 receiving recess of which said flange forms one wall, filler means seated in said recess and adapted to engage one side of the glass,

a glass seated in said frame and means for securing the glass firmly in seated relation upon said filler means.

25

7. A curtain window installation comprising, in combination, a frame presenting a portion adapted to be secured to the curtain and an outstanding flange approximately perpendicular to the plane of the curtain, a hollow cover frame on said first mentioned frame and secured thereto adjacent one edge, said outstanding flange being seated within and bearing against said cover frame, whereby to strengthen said frame 30 against transverse bending, said flange forming a filler receiving recess in said cover frame, filler means seated in said recess, a glass seated in said frame and means for pressing the glass firmly into engagement 35 with said filler means.

15 In testimony whereof, I have signed my name to this specification.

ALPHONSO S. CAMPBELL.
